CLAIM

The ornamental design for a nursing garment as shown and described.

DESCRIPTION

FIG. 1 is a perspective view of a nursing garment showing the new design.

FIG. 2 is a front view thereof.

FIG. 3 is rear view thereof.

FIG. 4 is a left-side view thereof.

FIG. 5 is a right-side view thereof.

FIG. 6 is a front view thereof, with cups of the nursing garment in a nursing position; and,

FIG. 7 is a front view thereof, with the cups of the nursing garment in an opened position.

In these drawings, the solid lines illustrate the claimed ornamental design, whereas broken lines illustrate unclaimed subject matter and form no part of the claimed design. The medium broken lines showing the mannequin in FIGS. 1-7 depict environment that forms no part of the claimed design. The small broken lines in FIGS. 1, 2, 4, and 5 depict portions of the nursing garment that form no part of the claimed design. The medium broken lines shown within the garment in FIGS. 1, 2, and 4-7 depict portions of the nursing garment that form no part of the claimed design.

1 Claim, 7 Drawing Sheets
